Inventor:

James B. Clark

United States Patent Office.

JAMES B. CLARK, OF PLANTSVILLE, CONNECTICUT.

Letters Patent No. 79,205, dated June 23, 1868.

IMPROVEMENT IN WHIFFLE-TREE PLATE.

The Schedule referred to in these Letters Patent and making part of the same.

TO ALL WHOM IT MAY CONCERN:

Be it known that I, JAMES B. CLARK, of Plantsville, in the county of Hartford, State of Connecticut, have invented a new and improved Whiffle-Tree Plate; and I do hereby declare that the following is a full, clear, and exact description thereof, which will enable others skilled in the art to make and use the same, reference being had to the accompanying drawings, making a part of this specification, in which—

Figure 1 is a front elevation of my invention attached to the whiffle-tree and cross-bar.

Figure 2 is a section of the same.

Figure 3 shows the separate parts of my invention.

Similar letters of reference indicate like parts.

My invention consists in the use or employment of three separate plates of cast metal, the first provided with a shaft in its centre, to which the second is fitted, and held in its place by the third.

A designates the first plate, B designates the shaft, and C the tenon on the end of the shaft B.

The second plate, D, has a bearing, E, made to fit the shaft B, also a larger bearing, F, made to fit the edge of the third plate, G, while the centre of the third plate G fits the tenon C.

The first and second plates A and D are provided with arms *h h h*, in which are screw-holes, for fastening the plates to the cross-bar K and whiffle-tree L. One arm, *h*, on each plate is turned or set at right angle with the plates, in order that two screws can be placed in the bottom of the whiffle-tree L, and two in the top of the cross-bar K, and one on the side of each, which secures the plates firmly in their places.

The shaft B, tenon C, bearings E and F, and the third plate G, can be turned, milled, or finished in any proper manner.

When the parts are fitted, place the second plate D on the first plate A, with the shaft B in the bearing E. Next, place the third plate G in the bearing F, with the tenon C through its centre, and secure it in its place by rivets through the holes *i i i*.

If desired, the tenon C and the centre of the third plate G might be threaded, and thus hold in its place the third plate G.

The tenon C might be made long enough to upset, and thus hold the third plate G in its place.

T, in fig. 2, designates a hole, which is filled by the whiffle-tree bolt M in fig. 1.

N N designate the rivets that hold the third plate G in its place. The plates thus held together make an easy-working joint, and one perfectly secure of itself, without the aid of the whiffle-tree bolt M.

By my invention I produce a whiffle-tree plate with a large bearing, holding the whiffle-tree firm in its place, and not liable to rattle. If neatly fitted, dirt or sand cannot get into the bearings, causing them to wear out.

Should the whiffle-tree bolt M, accidentally or otherwise, be removed, the plate will hold the whiffle-tree in its place, and consequently is a safeguard against accidents.

What I claim as new, and desire to secure by Letters Patent, is—

A whiffle-tree plate, with its shaft B, tenon C, bearings E and F, and third plate G, all constructed and operating substantially as described.

JAMES B. CLARK.
